UNITED STATES PATENT OFFICE.

BURTON H. LOCKE, OF ORANGE, MASSACHUSETTS.

TROUSERS-PRESSING DEVICE.

Application filed March 26, 1925. Serial No. 18,421.

To all whom it may concern:

Be it known that I, BURTON H. LOCKE, a citizen of the United States, residing at Orange, in the county of Franklin and State 5 of Massachusetts, have invented a new and useful Trouser-Pressing Device, of which the following is a specification.

My invention relates to improvements in trouser pressing devices, of the form where- 10 by trousers are pressed by means of applying a pressure or a squeeze to same, and the object of my invention is to produce a trouser pressing device that by reason of a squeezing element thereof permits rapid and 15 effective creasing of trousers and that by a simple stretching element thereof permits removal of wrinkles from trousers, without the use of moisture or heat in connection with same.

20 In the accompanying drawing:—

Figure 1 is a plan view of my trouser pressing device as same appears when pressing trousers.

Figure 2 is an end view of same from the 25 narrow end.

Figure 3 is a side view of same.

Figure 4 is an end view of the device as it appears when partly folded.

Figure 5 is a sectional view on line 5—5 30 of Figure 1, to an enlarged scale.

Figure 6 is a perspective view with several of the pressure strips in an open position.

My improved trouser pressing device com- 35 prises a base board or base plate 10 being, in this instance, composed of two equal sec- tions 11 and 12, which are fastened together at the inner edges 13 thereof by means of hinges 14. The base plate 10 could be con- 40 structed in one section instead of the two sections as shown and as described. The hinges 14 are adapted to permit sections 11 and 12 to fold on the faces 15 thereof, as best shown by Figure 4. The sections 11 45 and 12 have diverging outer edges 16.

It is obvious that the shape of the base plate 10, as shown by Fig. 1, corresponds to the general shape of a trouser leg.

On the diverging edges 16 of base plate 50 10 there are hinged by means of hinges 17 comparatively narrow strips 18. In this instance, there are two strips 18 hinged to each of said edges 16, but said strips 18 could conveniently be constructed in one section, or 55 could be composed of several sections hinged to each edge 16. Hinges 17 are adapted to

allow the face 19 of strips 18 to cooperate with the face 20 of base plate 10. Thumb screws 21 project through holes 22 in strips 18, and have threaded engagement with base 60 plate 10. In this instance, the base plate 10 and strips 18 are shown as being of wooden structure, and when this structure is used metal nuts 23 are secured in base plate 10, to form the said threaded engagement with 65 said thumb screws, and washers 23^a are provided in strips 18. However, I do not confine myself to this structure as these devices could be constructed of any suitable ma- 70 terial.

By means of thumb screws 21 individual pressure cooperation of face 19 of each of said strips 18 and face 20 of said base plate 10 is obtainable for the purpose of creasing trousers 27 which are held therebetween in 75 the process of being pressed. Other common practical clamping means for bringing each strip 18 in an individual pressure cooperation with base plate 10 could be used in lieu of that shown.

80 Hinges 17 are shown as being of a well known type of hinge, but any other practical hinge could be used in lieu of same.

There is a shallow notch 24 extending across the face 20 of base plate 10 at the 85 narrow end 25 thereof, and there is also a similar notch 26 extending across the cooperating face 19 of strips 18 positioned in co- operating relation to notch 24. Notches 24 and 26 are for the purpose of receiving the 90 cuffs of the trousers 27 when same are being pressed as previously described. Notches 24 and 26 are not required and same are omitted when cuffless trousers are to be pressed.

The inner cooperating corners 28 of strips 95 18 are rounded the entire length of same to prevent an objectional line or crease being made in trousers 27 at this point, as would be the case should these corners 28 be made sharp instead of being generously rounded. 100

Near each of the diverging edges 16 at the narrow end 25 of base plate 10 there is secured therein a hook-eye 29 which extends slightly outward therefrom and then backward beyond the face 15 of said base plate 105 an amount equal to about the thickness of the base plate 10 and strips 18. This particular amount of backward projection of hook-eyes 29 would allow a feature of compactness when the device is folded as previously described and as illustrated by 110 Fig. 4.

The purpose for extending hook-eyes 29 backward as described is to obtain a resulting force which would act to fold the two sections 12 and 13 backward on the face 15 of each when the said device is suspended by a cord 30 which passes through eyes 31 of said hook-eyes 29. This force would act to tighten and stretch the center portion 32 of the trousers 27, when same are intact, 10 producing a removal of wrinkles therefrom.

An explanation of the use of the device just described would be briefly as follows:—

The trousers 27 are placed on the base plate 10 in the position as shown in Fig. 1. 15 The strips 18 are secured in contact relation with said trousers one at a time by means of the respective thumb screws 21. The individual application of each strip 18 permits a smoothing of the trousers between each said 20 application of a strip, and therefore, permits a more correct insertion of the trousers than would be allowable by a combined clamping arrangement. The device can be then suspended by cord 30, which, as explained, 25 previously, causes a removal of wrinkles from the said trousers.

I do not confine myself to the exact details as the same are susceptible of modification without departing from the spirit or 30 scope of the invention.

I claim as my invention:—

1. A trouser pressing device comprising a base-board composed of two longitudinal sections, and a strip held in hinged relation to 35 the outer side of each section, said strips being positioned to cooperate with a common face of said base-board, and means for holding each strip in pressure cooperation with said common face of said base-board, and a 40 hinged connection between the two sections of said base-board, said hinged connection allowing the said sections to fold on the face

opposite the cooperating face thereof, for the purpose set forth.

2. In a trouser pressing device comprising 45 a base-board composed of two longitudinal sections, a plural number of strips held in hinged relation to the outer side of each section, and each of said strips positioned to cooperate with a common face of said base-board, and means for holding each strip in individual pressure cooperation with said common face of said base-board, and a hinged connection between the two sections 50 of said base-board, said hinged connection allowing the said sections to fold on the face opposite the cooperating face thereof, for the purpose set forth.

3. In a trouser pressing device as described in claim 1, a hook-eye secured near the outer 60 edge of the narrow end of each of said sections, each said hook-eye projecting outward therefrom and backward beyond the folding face of each of said sections and serving to receive a cord, for the purpose set forth. 65

4. A garment pressing device comprising a base member composed of a plural number of longitudinal sections, and pressing members at the outer sides thereof, said pressing members positioned to cooperate with a common face of said base member, and means for holding each pressing member in pressure cooperation with the said common face, and hinged connections between the sections of 70 said base member allowing said sections to 75 fold on each other, and a hook-eye secured near each of the outer sides of said base member at one end thereof, said hook-eyes extending outward therefrom and backward beyond the folding faces of the sections of 80 said base member to receive a cord, as set forth.

BURTON H. LOCKE.
